UNITED STATES PATENT OFFICE.

HENRY SUCK, OF ROSLINDALE, MASSACHUSETTS.

FASTENER FOR DOORS, PANELS, AND THE LIKE.

Application filed May 29, 1928. Serial No. 281,398.

This invention relates to fasteners for doors, panels and the like and particularly to a fastener of the type which is concealed when the door is closed but which may be actuated to release the door by giving the door a slight inward movement from its normal closed position.

The general object of my invention is to provide an improved fastener of this type which is simple in construction and inexpensive to manufacture but which is also effective in operation.

A fastener embodying my invention comprises a striker which may be on either the door or the door frame, and a vertically swinging latch which may be pivotally mounted either on the door frame or the door, the door being fastened by the engagement of the latch with the striker.

20 A further object of the invention is to provide a door fastener of this type in which the latch is released from the striker by the engagement of two co-operative faces on the striker and latch respectively during the spring-impelled opening movement of the door after it has been pushed inwardly beyond its normal closed position and then has been suddenly released.

Other objects of the invention are to provide various novel features of construction which will be hereinafter set forth.

In order to give an understanding of the invention I have illustrated in the drawings a selected embodiment thereof which will now be described after which the novel features will be pointed out in the appended claims.

In the drawings, Fig. 1 is a fragmentary view showing a portion of a door frame and a door equipped with my improved fastener, said view being on substantially the section line 1—1, Fig. 3;

Fig. 2 is a similar view showing in full lines the door after it has been pushed inwardly beyond its normal closed position preparatory to releasing the fastener, the dotted line position showing the action of the door in releasing the fastener;

Fig. 3 is a section on the line 3—3, Fig. 1 showing the fastener in plan view;

50 Fig. 4 is a perspective view of the latch member of the fastener;

Fig. 5 is a fragmentary view illustrating a different embodiment of the invention.

55 My improved fastener is adaptable for use in fastening doors of almost any description

having a properly placed door stop and also for fastening swinging panels and the like.

In the drawings I have shown at 1 a portion of a door frame and at 2 a portion of a swinging door which may be closed by a 60 swinging movement from the dotted to the full line position, Fig. 3.

The fastener comprises a striker member 3 which is secured to one of the door elements, that is, either to the door or to the door frame, 65 and which has a projection or finger 4, and a latch member 5 which is pivoted to the other door element and which co-operates with the projection 4 to fasten the door. In the construction herein shown this striker 3 is secured to the inside of the door by means of suitable screws 6 and the latch 5 is pivotally mounted to the door frame 1, although I wish it understood that the latch might be placed on the door and the striker on the door frame 70 without departing in any way from the invention.

The latch 5 is herein shown as pivotally mounted in a housing member 7 which is secured to the door frame through suitable 80 screws 8. This housing has a recess 9 in which the pivoted end of the latch is received, said latch being pivotally carried by the housing through the medium of a pivot pin 10. The latch projects beyond the housing 7 and 85 at its outer end it is provided with the inclined cam face 11 and with the locking shoulder 12 in the rear of said face. The striker and latch have such a relative position that when the door is being closed the finger 90

4 of the striker will engage the cam face 11 during the final closing movement of the door and by such engagement will raise the latch as usual in fasteners of this character. As the door is fully closed the nose 13 of the 95 latch will wipe over the striker and will drop behind the finger 4 which by its engagement with the shoulder 12 will restrain the door from opening movement.

My invention provides a novel construction 100 by which the latch may be released by quickly releasing the door, after it has been pushed inwardly slightly beyond its normal closed position.

The door frame is provided with a door 105 stop 14 which is so placed as to permit a slight inward movement of the door after the latch has engaged the striker. The full line position of the door in Fig. 3 is that corresponding to the position shown in Fig. 1 when the 110

door is latched by the engagement of the striker with the shoulder 12 and the stop 14 is so placed as to permit the door to move inwardly slightly from the full line position 5 Fig. 3 to the right hand dotted line position.

A spring is provided which acts on the door when the latter is closed tending to open it and if the door is suddenly released after having been pushed inwardly into the position shown in Fig. 2 the spring will give the door a quick outward or opening impulse.

The latch 5 and the striker 3 are provided with co-operating surfaces which function to raise the latch sufficiently to clear it from the striker when the door has its spring-impelled quick outward or opening movement. One of such co-operating surfaces is in the form of a cam projection which may be on either the latch or the striker. In the illustrated embodiment of the invention such projection is on the latch and is indicated at 15, said projection having the cam face 16. This cam projection is situated back of the shoulder 12 and is so located that when the door is moved inwardly slightly from its normally latched position the cam projection will ride over the finger 4 of the striker as shown in Fig. 2. If the door is released after having been moved into the full line position Fig. 2 the quick outward or opening impulse which is given to the door by the spring will cause the finger 4 to engage the cam face 16 and thus throw the latch 5 upwardly into the dotted line position Fig. 2. If the spring-impelled movement of the door is quick enough the door will be moved outwardly into the dotted line position, Fig. 2 and left hand dotted line position Fig. 3, before the latch can gravitate downwardly into its latching position. Hence the release of the fastener involves simply the operation of pushing the door inwardly slightly from its latched position and then quickly releasing it to allow the spring and the co-operating faces on the striker and latch to function to throw the latch upwardly 45 into inoperative position.

The spring which thus assists in the opening movement of the door may be of any suitable type or character and may be arranged to 50 act on any part of the door so long as it is constructed so that when the door is closed it is under tension and is ready to give the door a quick opening impulse after said door has been given its additional inward movement 55 into the position shown in full lines, Fig. 2, and then released.

As illustrating one practical construction I have shown a coil spring 17 which is carried in a recess 18 formed in the housing 7 and 60 which acts on a plunger 19 that is slidably mounted in the housing and projects beyond the same.

In order to prevent the pin from being ejected from the housing by the spring said pin is recessed on one side as shown at 20 and

the housing 7 carries a stop pin 21 extending transversely therethrough and occupying said recess. The engagement of the shoulders at the ends of the recess with the stop pin 21 limits its movement in either direction. Normally the plunger 19 projects considerably beyond the housing as shown in Fig. 4 and when the door is closed the striker engages the plunger and forces it inwardly thereby compressing the spring 17, the spring being partially compressed when the door is fastened by the engagement of the projection 4 with the latch 5.

When the door is given its additional inward movement into the full line position Fig. 2 the spring is additionally compressed and is then in a condition to give the door a quick opening impulse the instant that the pressure on the door is released.

In order that the latch may function easily and satisfactorily I propose to so shape it that the pivotal pin 10 is located below the plane of the nose 13 and the cam projection 15 as clearly shown in Fig. 2. With this arrangement the engagement of the striker with the cam surface 11 is at a point above the pivot so that the latch will be easily swung upwardly by the impact of the striker therewith to allow the finger 4 to wipe by the nose 13. When the latch is in locking position shown in Fig. 1 it is held slightly above normal position by the striker and the shoulder 12 is so formed that it will have a flat bearing against the striker when the latch is in this locking position. The partially compressed spring 17 will hold the striker against the latch.

When the door has been given its additional inward movement preparatory to unlatching the door and the striker has wiped under the cam projection 16, the latch is supported by the engagement of the surface 22 thereof with the finger 4. The latch has such a shape that when thus supported it is elevated still higher than when it is in locking position shown in Fig. 1. When, therefore, the pressure on the door is released and it is allowed to have its quick spring-impelled opening movement the latch is thrown upwardly by the engagement of the finger 4 with the cam surface 16 from a partially raised position and since the upward throw of the latch is started from a partially raised position the impact of the finger with the cam 16 will carry it upwardly sufficiently far so that the door will have plenty of time to move from the position shown in Fig. 2 to a position in which the finger 4 is beyond the reach of the latch 5 before such latch can gravitate into its normal position.

The nose 13 will preferably have the rounded inner corner 23 so that if the opening movement of the door was so sluggish as to allow the latch to drop into a position where the nose 13 would engage the finger 4 before said finger had been carried beyond the nose, the engagement of said finger with the rounded

corner 23 would throw the latch back again and prevent relatching of the door.

In Fig. 5 I have shown a slightly different embodiment of the invention which is specifically adapted for larger fasteners to be used on heavier doors. In this embodiment the cam projection is provided with a protuberance 25 which is situated to be engaged by the finger 4 of the striker when the door is released after its inward movement. The engagement of the finger 4 with this protuberance will give the latch an additional upward impulse which will ensure its being thrown backwardly to its limit even though it is relatively heavy as would be necessary on a heavy door.

It will be seen that the device is extremely simple and that the releasing of the latch is accomplished by the inter-engagement of two co-operating faces, one on the latch and the other on the striker and further that the latch is raised by the spring-impelled movement of the door when it is released after it has been pushed inwardly beyond its latching position. With this invention, therefore, the latch is released by the initial spring-impelled outward opening movement of the door rather than by the initial movement beyond the normal latched position. While I have illustrated herein a selected embodiment of the invention I do not wish to be limited to the constructional features shown.

I claim:

1. In a door fastener, the combination with a door element and a frame element, of a striker on one of said elements, a vertically-swinging latch pivoted to the other element and co-operating with said striker to fasten the door, a spring acting on the door when closed and tending to open it, said door being capable of having a slight additional inward movement beyond its normal closed position, and means rendered operative by the initial spring-impelled opening movement of the door after it has been given its additional inward movement to clear the latch from the striker and thus release the fastener.

2. In a door fastener, the combination with a door element and a frame element, of a striker on one of said elements, a vertically-swinging latch pivoted to the other element and co-operating with said striker to fasten the door, a spring acting on the door when closed and tending to open it, said door being capable of having a slight additional inward movement beyond its normal closed position, said latch and striker having co-operating surfaces which function to raise the latch sufficiently to clear it of the striker during the initial spring-impelled opening movement of the door.

3. In a door fastener, the combination with

a door frame element and a door element, of a striker on one of said elements, a vertically-swinging latch pivotally mounted on the other element and having a nose to co-operate with the striker to hold the door closed, a spring acting on the door when in closed position and tending to open it, said door being capable of having a slight additional inward movement after the latch is in latching engagement with the striker, said latch having a cam projection which wipes over the striker during such additional movement, whereby when the door is quickly released after such additional movement the initial spring-impelled movement of the door will cause the striker to engage the cam projection and thus to clear the latch from the striker while the door is opening.

4. In a door fastener, the combination with a door frame element and a door element, of a striker on one of said elements, a vertically-swinging latch pivoted to the other of said elements and having a nose to co-operate with the striker to hold the door closed, said door being capable of having a slight additional inward movement beyond that necessary to bring the latch into latching engagement with the striker, said latch having a cam projection under which the striker wipes during such additional movement, and a spring acting on the door when closed and tending to open it, whereby when the door is given such additional inward movement and then is quickly released the engagement of the striker with the cam projection due to the spring-impelled opening movement of the door will throw the latch upwardly sufficiently to clear the striker as the door opens.

5. In a door fastener, the combination with a door frame element and a door element, of a striker on one of said elements, a vertically-swinging latch pivoted to the other of said elements and having a nose to co-operate with the striker to hold the door closed, the pivotal point of the latch being below the level of the nose, said door being capable of having a slight additional inward movement beyond that necessary to bring the latch into latching engagement with the striker, said latch having a cam projection under which the striker wipes during such additional movement, and a spring acting on the door when closed and tending to open it, whereby when the door is given such additional inward movement and then is quickly released the engagement of the striker with the cam projection due to the spring-impelled opening movement of the door will throw the latch upwardly sufficiently to clear the striker as the door opens.

In testimony whereof, I have signed my name to this specification.

HENRY SUCK.
